DESIGN FOR A DISH.

No. 39,401.

Specification for Design.

Patented July 7, 1908.

Application filed February 17, 1908. Serial No. 416,425. Term of patent 7 years.

To all whom it may concern:

Be it known that I, PAUL R. ZINSER, a subject of the Emperor of Germany, residing at Cincinnati, in the county of Hamilton and State of Ohio, have invented a new, original and ornamental Design for a Dish, of which the following is a specification, reference being had to the accompanying drawing, forming part thereof.

In the drawings, Figure 1 is a top plan view of the dish, and Fig. 2 is a side elevation of the same.

I claim:

The ornamental design for a dish, as shown.

PAUL R. ZINSER.
